Philippe Alexandre, La Tronche, France, assignor to Societe Grenobloise d'Etudes et d'Applications Hydrauliques, Grenoble, France, a corporation of France

Filed Apr. 18, 1958, Ser. No. 729,336

Claims priority, application France July 24, 1957
10 Claims. (Cl. 61-18)

This invention relates to hydraulic apparatus and more especially to hydraulic modules designed to control flow of hydraulic fluid or water so as to discharge a constant volume with varying levels or pressure heads upstream of the apparatus.

Apparatus of this type has been constructed heretofore utilizing one or more baffles disposed within a flow chamber or channel, these baffles cooperating with generally vertical lateral walls of the chamber and with a bottom or base wall to form one or more orifices through which the discharge is effected and by means of which the flow is controlled. When a plurality of such baffles are used one baffle is disposed downstream with respect to another baffle and it has been found desirable to position the downstream baffle in the chamber so that it forms with the bottom wall of the chamber an orifice of reduced area with respect to the area of the orifice similarly formed by the upstream baffle. In such a construction utilizing a plurality of baffles also it has been proposed that the baffles be so formed and disposed as to direct the flow which occurs between two baffles, upon overflow of the upstream baffle of the two, against the water flowing through the orifice provided beneath the upstream baffle.

The operation of a module having two baffles is carried out in the following manner:

As the head of water increases so that the level of the water in the module upstream of the first baffle rises, this first baffle is first engaged and the flow of the water through the orifice provided by the first baffle is determined by this first orifice under the head due to the level of the water in the module. The water level continuing to rise, when it reaches the height of the top of the first baffle the water will overflow this first baffle and fall into the space between the two baffles. Upon further rise of the water level sufficient water will overflow the first baffle to fill the space between the two baffles and to effect flow downwardly through this space, this downward flow meeting the generally horizontal flow which is occurring beneath the first baffle.

When the water rises further and a head of water is developed in the module by the water rising to a level substantially above the first baffle, the flow in the downstream direction is determined generally by the second orifice. This flow, however, is modified by the effect of the submerged orifice through which a part of the water flows between the lower edge of the first baffle and the bottom wall of the flow chamber and is further modified by directing, as above mentioned, the flow of the water in the space between the two baffles angularly downward in the upstream direction against the stream of water flowing beneath the first baffle. This may be accomplished by forming and disposing the two baffles with lower portions inclined to the horizontal and downwardly in the upstream direction.

In conventional modules having two baffles, for a given loss of head and a given allowable variation of the discharge above and below a normal discharge, by making the downstream orifice defined below the second baffle of less area than the upstream orifice defined below the first baffle, the discharge may be controlled to a greater extent by the downstream baffle when the water

2

level is high and the head required for effecting the downstream flow through the orifices is therefore greater, so that the module may be operated with a considerable rise of the upstream level above the normal level. The lower edges of the two baffles in a conventional module are horizontal.

Tests carried out by the applicant, however, have shown that, in order to increase the control characteristics of a module without changing the inclination of the baffles which, as mentioned above, directs the flow between the two baffles in the upstream direction toward the upstream orifice, it is necessary to substantially diminish the area of the downstream orifice as compared to conventional practice, that is to say, it is necessary to place the downstream baffle as low as possible while avoiding a position for this baffle which will cause it to be engaged by the water flowing through the upstream orifice before the upstream baffle is engaged. If the downstream baffle were first engaged the condition might occur that a very small discharge would take place which might be less than the minimum allowable discharge. While it is desirable for the reasons mentioned above to have the downstream baffle and its orifice control the flow when the water level is at a substantial height in the module and with the upstream baffle submerged, it is undesirable that the downstream orifice shall control the flow when the water level in the module is low and at such height, less than the level of the top of the first baffle, that the water is flowing only through the first orifice beneath the first baffle and not through the space between the two baffles.

In the conventional module the lowest position in which it is normally possible to dispose the second or downstream baffle is determined by the condition that this baffle shall not engage the sheet of water flowing through the upstream orifice when the sheet of water is on the point of being engaged by the first or upstream baffle.

It has been shown by tests carried out by the applicant that an advantageous effect is secured by modifying the lower edge of the upstream baffle. If, for example, the lower edge of this upstream baffle, instead of being horizontal, is formed with an inclination from one lateral wall to the other, it becomes possible to begin the engagement of the upstream baffle before this baffle would be engaged if its edge were horizontal. If the area beneath the inclined edge of the baffle is made equal to the required area for the orifice utilizing a horizontal edge, it will be understood that the lower part of the inclined edge dips into the rising water at the very beginning of the engagement of the baffle by the water and that the portion of the edge engaged continuously increases as the water rises, the full area of the orifice not being utilized until the water level reaches the higher end of the inclined edge of the baffle. The total flow area being substantially the same as with a horizontal lower edge, the discharge of the water through this orifice for any given head will remain substantially the same.

It will be understood further with this form of baffle utilizing an inclined edge or an edge of such contour that it initially does not engage the water stream for the full extent of this edge, that the flow area is gradually increased as more and more of the edge becomes submerged but the full restriction is not developed at once as when the horizontal edge engages the water stream. The form of the stream flowing from the first baffle starts to be modified by the portion engaged, however, so that the lower edge of the second or downstream baffle may be disposed at a lower point than otherwise would be the case if the edge of the first baffle were horizontal. Consequently, the area of the orifice at the second baffle is reduced and the rise of the level above the normal level necessary to produce a given flow through the

module is required to be greater, so that the upstream level of water may increase substantially as compared with a conventional module.

It is an object of the invention, with a view to securing improved operating characteristics above mentioned, to provide for the upstream baffle a profile of its lower edge such that a varying area of flow beneath this baffle is secured as the water rises following first engagement of the lowermost portion of the baffle. In practice the outline of this profile will be such that the area of the orifice below the first baffle will be the same as would be required for a rectilinear horizontal conventional profile.

Other objects and features of the invention will be understood from the description to follow taken in connection with the drawings in which—

FIG. 1 is a longitudinal section of a module according to the invention operating with the upstream orifice controlling the flow;

FIG. 2 is a longitudinal section of this module operating with the downstream orifice controlling the flow;

FIG. 3 shows in elevation a baffle according to the invention;

FIG. 4a shows a modification of this baffle, and

FIG. 4b shows a further modification of the baffle.

In FIG. 1 the module is constructed with a conventional sill or bottom wall 1 upon which are erected lateral walls 3 extending generally parallel to the direction of flow of the hydraulic fluid, these vertical walls 3 being spaced apart transversely of the direction of flow. A cross section of the module is diagrammatically shown in FIG. 3 in which the sill 1 is shown as a base wall and the lateral walls are shown as parallel vertical side walls of the flow chamber or channel.

Spanning between the lateral walls is an upstream baffle 5 disposed with its planar extent inclined to the horizontal and with its lower edge 7 spaced vertically above the base wall 1, as shown in FIGS. 1 and 2. As shown in FIG. 3 in the modification being described the lower edge 7 of this baffle is rectilinear but disposed at an inclination to the horizontal, the area defined by the edge 7 and the base wall 1 and the lateral walls 3 being substantially equal to an area represented by the dotted outline 9 for the horizontal lower edge of a baffle of conventional form.

As above indicated, as the water rises in the chamber above the base wall 1 and just comes into engagement with the lowest point of the edge 7 of the baffle 5, the area of flow is represented by a rectangle having the height of this lower end point of the edge 7 and a width equal to the distance between the lateral walls 3. As the water rises further into engagement with the baffle, the lower edge 7 gradually becomes submerged until the water level reaches the height of the upper end of the edge 7. The area through which the water flows when the edge 7 is thus fully submerged is equal to the area beneath a conventional baffle when the edge 9 of such conventional baffle just starts to be submerged. It will be understood that the baffle with the inclined edge, therefore, has been effective to control the flow through the orifice earlier in the rise of the water upon the baffle and to restrict this flow more than if, for the same area, during the development of the full flow area of the orifice the lower edge of the baffle were horizontal.

When the water has risen to any height, for example h_1 in FIG. 1, the orifice beneath the inclined edge 7 is effective to control the flow, the stream taking the form with the profile S_1 generally as shown in FIG. 1. The water may continue to rise in engagement with the baffle 5 until it reaches the top 11 of the baffle 5, this top portion in the embodiment shown in the drawing being of arcuate form so that, when the water overflows this top portion 11, it will flow over a smoothly curved surface into the space between the baffle 5 and the downstream baffle 13. It will be understood that under these condi-

tions the gate 31, hereinafter further described, will be raised to the open position as in FIG. 2.

In the embodiment shown in FIG. 1 the downstream baffle 13 is formed with a vertically disposed wall in spaced relation downstream with respect to the curved portion of the baffle 5. The baffle 13 also has a reverted portion 15 directed downwardly and upstream in angular relation to the horizontal and to the flow from the upstream orifice and generally parallel to the extent of the baffle 5. The water overflowing the portion 11 of the baffle 5 will fall through the space between the baffles until, as the water in the module continues to rise, a level is reached at which the flow between the two baffles fills the space therebetween and the lower edge 17 of the downstream baffle 13 becomes effective to control the discharge from the module. The level may continue to rise to some level h_2 as in FIG. 2 which determines a flow through the orifices and a form of the stream as at S_2 . This flow, however, to a certain extent will be the result of the effect of the now submerged orifice at the edge 7 of the first or upstream baffle and of the effect of the angularly directed flow occurring between the inclined portions of the baffle 5 and the baffle 13.

It will be noted in connection with FIGS. 1 and 2 that the lower edge 17 of the baffle 13 is disposed at a lower lever than the lower edge 7 of the baffle 5. It will be noted from FIG. 1, however, that the lower edge 17 of the baffle 13 is not disposed at such a low level as to engage or interfere with the steam of the water issuing from the upstream orifice below the lower edge 7 of the baffle 5 when this baffle alone controls the flow. Nevertheless, when the orifice at the edge 17 becomes effective as in FIG. 2 to control the flow from the module, a greater head of the water in the module, that is to say a greater rise in the upstream level of the water, is required to produce the desired discharge because of the reduction of the area of the orifice at the edge 17 of the baffle 13 made possible due to the form of the lower edge of the upstream baffle 5, as described. Although this upstream head may be greater, the discharge flow remains restricted by the smaller area of the downstream orifice cooperating with the effect of the submerged orifice at the upstream baffle and the reverted flow between the two baffles directed upstream.

In FIG. 4a is shown a modification of the upstream baffle 5 of the invention in which the lower edge is formed with two portions 19 that are in inclined relation to the horizontal and extend oppositely from a central point 21 upwardly to the vertical edges of the baffle at the lateral walls 3. In this case also the area defined by the lower edges 19 above the floor or base wall 1 of the module may be equal to the corresponding area of a horizontal edge 23 indicated in dotted line in FIG. 4a for a conventional baffle.

FIG. 4b shows another modification of the lower edge of the baffle of the invention in which a central part of the baffle 5 has a horizontal edge portion 25 which is in stepped relation to two laterally disposed horizontal portions 27. The edge portions 25 and 27 may be disposed with reference to the base wall 1 of the channel so that the area defined by the edges 25, 27 is the same as for a conventional baffle having a continuous horizontal lower edge 29, as shown in dotted line in FIG. 4b.

In each of the modifications of FIGS. 4a and 4b it will be understood that a portion of the lower edge of the baffle is engaged by the rising water before another portion of this lower edge, so that the lower portion of this edge becomes submerged and, therefore, begins to determine the orifice and the flow before the edge is fully submerged. Restriction of the flow and contraction, therefore, take place which makes it possible to dispose the downstream or second baffle with its edge at a lower position than would be the case if the lower edge of the upstream baffle were horizontal.

The module shown in FIGS. 1 and 2 is provided with

a closing gate 31 which is supported by means not shown between the lateral walls 3 of the module, and preferably, downstream with respect to the downstream baffle 13, for vertical movement between open and closed positions. The gate 31 carries a plate 33 having upper and lower ends bevelled with respect to the horizontal for engagement by a clevis or clevis 35 which is pivotally supported on a shaft 37 which extends horizontally between and is supported by the vertical lateral walls 3. A lever 39 also is pivotally supported on this shaft 37 for movement between the two positions shown respectively in FIG. 1 and in FIG. 2. In FIG. 1 the lever 39 is held against movement by a bolt 41 insertable in an opening 43 in the wall 3 of the module and, in the position of FIG. 1, passing through a hole 45 in the lever 39. Attached to the clevis 35 also is a counterweight lever 47 which biases the clevis 35 in the counter clockwise direction upon the axis of the shaft 37 and serves for operating the clevis 35.

When the gate 31 is in the lowermost position as shown in FIG. 1 engaging the base wall 1 and shutting off the flow through the module it may be locked in this position by the clevis 35 engaging the upper bevelled end of the plate 33. The arm 47 tends to hold the clevis 35 in the position shown in FIG. 1 but the disposition of this clevis and of the upper bevelled edge of the plate 33 are such with respect to the shaft 37 that any upwardly acting force due to the vertical movement of the gate 31 will tend to move the clevis 35 in the counter clockwise direction on the shaft 37 and, therefore, into jamming engagement with the plate 33 to prevent such upward movement.

When it is desired to raise the gate 31 the bolt 41 may be withdrawn from the holes 43, 45 and the lever 39 moved pivotally clockwise upon the shaft 37 to the position shown in FIG. 2 in which the clevis 35 is out of engagement with the upper bevelled edge of the plate 33 by virtue of the clevis pivoting upon the shaft 37 with respect to the lever 39. This may be accomplished because, as the clevis 51 carried by the lever 39 is moved clockwise upon the shaft 37 and away from the plate 33, this clevis 35 which is otherwise blocked by the clevis 51 also may move away from the plate with the lever 39 and the clevis 51. Engagement of the clevis 35 with the upper inclined edge of the plate 33 for this released condition does not prevent this movement because of the bevelled upper edge of the plate 33 and the pivoting of clevis 35 on the shaft 37.

In the position of the clevises 35 and 51 and the lever 39 as shown in FIG. 2 the gate 31 may be raised to the position shown in which the lower bevelled edge of the plate 33 is above the clevis 35. This clevis then may be moved counter clockwise about the shaft 37 by moving the lever 47 downward, or by moving the lever 39 downward so that the clevis 51 effects movements of clevis 35 toward the plate. The bolt 41 then may be inserted in the holes 43 and 45. Such movement of the clevis 35 causes it to engage the plate 33 and to support the gate against downward movement, so that the water may flow through the orifices as above described. It will be noted that the lower edge of the gate 31 in this raised position is such as not to interfere with the flow through the downstream orifice at S_2 .

The gate may be provided with a stop element 55 which may serve to limit both the upward movement and, if desired, the downward movement by engagement with stop elements carried by the walls 3.

It will be understood that the invention includes within its scope baffles having outlines or contours of the lower edges thereof of different forms which provide for the variation of the height of the orifice beneath the baffle along the lower edge from one lateral wall of the module to the other. Such a lower edge may form with the base wall and lateral walls in some cases a symmetrical orifice, as in FIGS. 4a and 4b, or an orifice of unsymmetrical

form as in FIG. 3. Moreover, the outlines of these lower edges may be other than rectilinear provided the variation in height along the edge proceeding from one lateral wall to the other is secured which causes an effective part of the lower edge to become engaged before and to be submerged before another effective part is submerged as the water rises.

It will be understood further that the invention may be utilized in modules having more than two baffles as described in the present embodiment and, moreover, that a downstream baffle of a plurality of baffles may be provided with a lower edge having a contour of varying height for the same effect and purpose as described herein with respect to the upstream baffle of two such baffles in order that the flow may be controlled in the manner described through the orifice formed beneath the lower edge of such downstream baffle.

I claim:

1. A hydraulic module comprising a base wall extending generally in the direction of flow of the hydraulic fluid, opposed lateral walls extending transversely of said base wall and generally in said direction of fluid flow in spaced relation to each other, a first flow determining baffle disposed with its surface extent transverse to said lateral walls and transverse to said base wall and extending upwardly from the latter to a given level, said baffle having an edge disposed toward said base wall and extending transversely of said lateral walls in spaced relation to said base wall and forming one side of an orifice for the hydraulic fluid, said baffle edge being configured so that portions thereof are encountered by the fluid before other portions thereof during a rise in the level of the fluid flowing through such orifice, and a second baffle disposed in spaced relation to said first baffle in the downstream direction and with its surface extent transverse to said lateral walls and transverse to said base wall, said second baffle having a lower edge extending transversely of said lateral walls in spaced relation to and above said base wall and defining with said base wall and said lateral walls a second flow orifice of less area than the orifice defined in part by said first baffle edge.
2. A hydraulic module comprising a base wall extending generally in the direction of flow of the hydraulic fluid, opposed lateral walls extending transversely of said base wall and generally in said direction of fluid flow in spaced relation to each other, a first flow determining baffle disposed with its surface extent transverse to said lateral walls and transverse to said base wall and extending upwardly from the latter to a given level, the lower edge of said baffle extending transversely of said lateral walls in spaced relation to and above said base wall and forming with the latter and said lateral walls a flow orifice, said lower baffle edge being configured so that portions thereof are encountered by the fluid before other portions thereof during a rise in the level of the fluid flow through such orifice, and a second baffle disposed in spaced relation to said first baffle in the downstream direction with its surface extent transverse to said lateral walls and transverse to said base wall, the lower edge of said second baffle extending transversely of said lateral walls in spaced relation to and above said base wall and defining with said base wall and said lateral walls a second flow orifice of less area than the orifice defined in part by said lower edge of said first baffle.
3. A hydraulic module such as defined in claim 2 in which said lower edge is rectilinear and increases in height above said base wall in the length of said edge substantially from one of said lateral walls to the other.
4. A hydraulic module such as defined in claim 2 in which said lower edge comprises two portions oppositely extending from a low point thereon upwardly to respective points adjacent said opposite lateral walls.
5. A hydraulic module such as defined in claim 2 in which said lower edge comprises a plurality of generally

horizontal portions disposed in vertically stepped relation to each other.

6. A hydraulic module such as defined in claim 2 including a shut off gate disposed downstream with respect to said second baffle and with its surface extent transverse to said direction of flow, said gate being supported for vertical movement thereof into engagement at its lower edge with the stream of fluid flowing from said second orifice and upon continued movement through said stream into engagement with said base wall to stop the flow of said fluid.

7. A hydraulic module comprising a base wall extending generally in the direction of flow of the hydraulic fluid, opposed lateral walls extending transversely of said base wall and generally in said direction of fluid flow in spaced relation to each other, a first flow determining baffle disposed with its surface extent transverse to both said lateral walls and said base wall and extending upwardly from the latter to a given level, the lower edge of said baffle extending transversely of said lateral walls in spaced relation to and above said base wall and forming with the latter and said lateral walls a flow orifice, a second baffle disposed in spaced relation to said first baffle in the downstream direction with its surface extent transverse to said lateral and base walls, the lower edge of said second baffle extending transversely of said lateral walls in spaced relation to and above said base wall and defining with said base wall and lateral walls a second flow orifice of less area than the orifice defined in part by said lower edge of said first baffle, a shut off gate disposed downstream with respect to said second baffle and with its surface extent transverse to said direction of flow, said gate being supported for vertical movement thereof into engagement at its lower edge with the stream of fluid flowing from said second orifice and to a closed position in which it is in engagement with said base wall to stop the flow of such fluid, and means for locking said gate in its closed position and for supporting it in a position in which the lower edge thereof is positioned above such stream of fluid, said last mentioned

means comprising a pair of vertically spaced locking elements fixedly secured to the upstream side of said gate, a shaft extending transversely of said lateral walls and supported thereby, a locking member supported on said shaft for pivotal movement about the axis of the latter and engageable with the upper one of said locking elements to lock said gate in closed position and engageable with the other lower locking element to support said gate above said stream of fluid, means normally biasing said locking element into engagement with said elements, a lever supported on said shaft for pivotal movement about the axis of the latter and operable to withdraw said locking member from locking engagement with a locking element against the biasing action of said biasing means, and means for securing said locking member in locking engagement with a locking element.

8. A hydraulic module such as defined in claim 7, in which said gate carries a plate having upper and lower ends bevelled with respect to the horizontal, said bevelled ends constituting said pair of vertically spaced locking elements.

9. A hydraulic module such as defined in claim 7, in which said biasing means comprises a counterweight provided on said locking member so that it normally tends to pivot said locking member on said shaft in a direction to bring the locking element engaging portion of such member into latching engagement with such locking elements.

10. A hydraulic module such as defined in claim 7, in which said securing means comprises latch means for securing said lever to a lateral wall when said locking member is in locking engagement with either of said locking elements.
